Chas. L. S.

John H. Partridge, of Roxbury, Mass.
Letter Patent No. 1446, Dated May 17, 1854.
Design for a Lady's Hat.

The schedule referred to in these Letter Patent and making part of the same.

To all Persons to whom these Presents shall come:

Be it known that I

John H. Partridge (a resident of Roxbury, in the County of Norfolk and State of Massachusetts), have invented or produced a new and useful and ornamental Design for a Lady's Hat; and I do hereby declare the same to be fully described in the following specification, and represented in the accompanying drawings, of which -

Figure 1. is a top view of the said hat.

Figure 2. a side view of it.

Figure 3. a longitudinal section of it.

Figure 4. a transverse section of it.

Figures 5 and 6. are diagonal sections taken on the lines a, b, and c, d, of figure 1.

Figure 7. is a transverse section, taken on the line e, f, of figure 1.

The crown A, of the hat is of an elliptical oval shape or an approximation thereto and slightly convex. The body B, at its base is also elliptical or oval and larger than the crown. The said body bevels more in rear than it does in its front.

The rim C, is turned up in front as shown at f, and down behind as represented at g, and is also curved on its edge, from front to rear, as shown in figures 1 and 2.

The rim not only turns up in front relatively to the body, but as it rises upward it is curved away or over from the body, more or less, all around the rim, until it meets the

back part q.

The rear part q. is concavo convex, the convexity being on its upper side, the whole being as represented in the drawings.

This design of hat in order to distinguish it from others in the market. I term the "Oriole".

I claim the ornamental design as herein before described, and delineated . . . in the aforesaid drawing.
